UNITED STATES PATENT OFFICE.

ISAAC M. PEASE, OF CINCINNATI, OHIO.

TRUSS PAD.

Application filed September 20, 1926. Serial No. 136,562.

This invention aims to provide novel means for connecting a truss pad to a post or standard in such a way that the pad may be rotated on the standard, and slid freely 5 on the standard, longitudinally of the standard, novel means being provided for holding the pad in place on the standard.

It is within the province of the disclosure to improve generally and to enhance the 10 utility of devices of that type to which the invention appertains.

With the above and other objects in view which will appear as the description proceeds, the invention resides in the combination 15 and arrangement of parts and in the details of construction hereinafter described and claimed, it being understood that changes in the precise embodiment of the invention herein disclosed, may be made 20 within the scope of what is claimed, without departing from the spirit of the invention.

In the drawings:—

Figure 1 shows in perspective, a device constructed in accordance with the invention; 25

Figure 2 is a composite perspective view wherein the parts are separated;

Figure 3 is a sectional view taken through the post or standard;

Figure 4 is a cross section on the line 4—4 of Figure 3;

Figure 5 is a view like Figure 4, but showing a modification.

The truss pad 1 includes a back plate 2 having a hub 3 provided with a smooth circular opening 4 wherein a post or standard 5 is mounted to slide freely, lengthwise, and to rotate freely. The standard 5 has longitudinal ribs 6 defining longitudinal grooves 9.

A clamping device 7 is provided, and the same may be a screw, threaded into the hub 3, the inner end of the screw 7 being engaged as shown at 8 in one of the grooves 9 between the ribs 6.

The standard 5 has a head 10 cooperating with an arm or other support 11 that is provided with a slot 12 wherein a screw 14 is adjustable, the screw 14 being threaded into the bore 15 of the standard 5, and including a head 16 which clamps the arm 11 against the part 10, the head 16 of the screw being equipped with a pivoted bail 17 or the like, whereby the screw 14 may be adjusted in and out.

When the screw 7 is retracted, so that its

inner end is not engaged, as at 8, in one of the grooves 9, of the standard 5, the standard 5 may be shifted freely, in the direction of its length, in the hub 3, and the standard 5 also can be rotated freely in the hub 3. 60 After the standard 5 has arrived at the proper position with respect to the hub 3, the standard may be held in its adjusted position, by advancing the screw 7 until its inner end is engaged as at 8 in one of the grooves 9 of the standard 5. The construction is such that the pad 1 may be made to exert more or less pressure on the rupture, as occasion may demand.

The construction of the standard 5 with 70 respect to the hub 3 has many advantages over a form wherein the standard is threaded into the hub. In the device forming the subject matter of this application, the rotary adjustment of the truss pad 1 on the 75 standard 5 is independent of the adjustment of the truss pad lengthwise of the standard 5. The operator can move the truss pad 1 lengthwise of the standard 5 without rotating the truss pad on the standard; he can 80 rotate the truss pad without shifting it longitudinally of the standard; and he can both rotate the truss pad on the standard and shift the truss pad lengthwise of the standard, the parts being held, in any event, 85 when the screw 7 is advanced into one of the grooves 9.

In Figure 5, parts hereinbefore described have been designated by numerals previously used, with the suffix "a". The modification 90 consists in omitting the longitudinal grooves 9 of Figure 4 from the standard 5^a of Figure 5.

What is claimed is:—

1. In a device of the class described, a 95 truss pad provided with a hub having a smooth bore, a standard rotatable in the bore and slidably longitudinally in the bore, the standard being provided with circumferentially spaced longitudinal grooves, a 100 clamping device movable in the hub and adapted to be engaged in any of the grooves, a support, and means for assembling the standard with the support.

2. A truss pad having a smooth bore, a 105 standard rotatable in the bore and slidably longitudinally in the bore, the standard having longitudinal grooves, and a screw threaded into the pad and adapted to be received in any of the grooves, to prevent 110

the standard from rotating in the bore and to prevent the standard from moving longitudinally in the bore.

3. In a device of the class described, a truss pad provided with a hub having a smooth bore, a standard rotatable in the bore and slidale longitudinally in the bore,

and a clamping device movable in the hub and engaging the standard.

In testimony that I claim the foregoing ¹⁰ as my own, I have hereto affixed my signature.

ISAAC M. PEASE.
